UNITED STATES PATENT OFFICE.

GEORGE LEMIEUX, OF WASHBURN, WISCONSIN.

RAILROAD-TIE.

938,003

Specification of Letters Patent. Patented Oct. 26, 1909.

Application filed March 26, 1909. Serial No. 485,943.

To all whom it may concern:

Be it known that I, GEORGE LEMIEUX, a citizen of the United States, residing at Washburn, in the county of Bayfield and State of Wisconsin, have invented new and useful Improvements in Railroad-Ties, of which the following is a specification.

This invention relates to railroad ties and rail securing devices therefor, and the object 10 of the invention is to provide a device of this character which is extremely simple in construction, cheap to manufacture, and which will perform the functions for which it is intended with efficiency.

15 With the above, and other objects in view which will appear as the description progresses, the invention resides in the novel construction and arrangement of parts herein-after fully described and claimed.

20 In the accompanying drawings there has been illustrated a simple and preferred embodiment of the invention and in which:

Figure 1 is a top plan view of the improvement illustrating the same in applied position under a pair of rails. Fig. 2 is a longitudinal sectional view on the line 2—2 of Fig. 1. Fig. 3 is a transverse sectional view upon the line 3—3 of Fig. 1. Fig. 4 is a detail side elevation of the locking dog.

30 It is the primary object of the present invention to construct a railroad tie provided with means whereby the rails may be attached thereto, which is not only simple and inexpensive in construction but which will 35 withstand the continuous pounding of the rolling stock as well as being practical and immune from the inclemency of the elements.

In the accompanying drawing there has 40 been illustrated a device which from practice has been found to overcome the difficulties or deficiencies above described.

In the accompanying drawing the numeral 1 designates the tie member. This tie is constructed of cement or other plastic material 45 and as shown in the drawings, is preferably of a rectangular formation. The cement tie 1 is reinforced by a suitable U-shaped metal boxing or core designated by the numeral 2. This boxing or core 2 is of a length and width slightly less than the tie member and is provided upon its top and sides with a plurality of recesses or openings 3 whereby the cement may be securely connected

with the core. By this arrangement it will 55 be noted that the tie 1 is not only fastened to the core at its top and sides, but at the same time the plastic material fills the entire body of the U-shaped boxing and this provides a strong and effective tie. 60

In order to connect the rails 4 upon the tie, the core or boxing 2, as well as the tie 1 are provided with vertical openings or cut-away portions 5. These cut-away portions 5 are positioned adjacent the ends of 65 the tie 1 in spaced relation with each other so as to be arranged in pairs which are adapted for the reception of suitable locking dogs 6. The dogs 6 are each provided with a depending portion or body 7 provided upon one of its edges with a rectangular slit or cut-away portion 8 from which projects an overlying lip 9, while the opposite edge of the said dog 7 is also provided with an offset portion or extension 10. The 70 tie 1 as well as the core 2 are both provided with suitable transverse openings 11 which are adapted for the reception of keys 12. These keys are substantially wedge-shaped in side elevation and have one of their ends 80 slit so as to provide means whereby the same will be securely attached to the tie 1 after passing through the openings 11 and the cut-away portion 8 of the dog 7. It is to be understood that the overlying lip 9 of the 85 dog 7 is arranged at an angle corresponding with the inclined base flange of the rails 4 so that when the key 12 is positioned within the slots the said portion 9 will effectively engage the upper faces of the flanges of the 90 rails and the offset portion 10 will be positioned upon the face of the core opposite the said lip 9. By this construction it will be noted that I have provided an extremely 95 simple and effective device for the purpose intended, one which may be cheaply constructed, which is effectively reinforced by the core 2, and which provides devices for effectively locking the rail upon the tie without necessitating the use of nuts, bolts or 100 the like.

Having thus described the invention what is claimed as new is:—

In a railroad tie and rail connecting members therefor, the combination with a plastic 105 body having a U-shaped metallic core, provided with openings in its top alining with vertical openings in the tie, locking dogs in

said openings, said dogs being provided with a body portion having a head extending from each of its sides and adapted to engage the flanges of the rails and the top of the ties, the body portions of said dogs having their adjacent faces provided with cut-away portions, and wedge-shaped securing members adapted to be inserted within the transverse openings in the tie and the reinforce-

ment thereof to retain the dogs in position 10 upon the rails and the tie.

In testimony whereof I affix my signature in presence of two witnesses.

GEORGE LEMIEUX.
